UNITED STATES PATENT OFFICE.

SAKUSHIRO HATAKEYAMA, OF SHIMOYAMATE DORI, KOBE, JAPAN, ASSIGNOR OF ONE-HALF TO CHOJI FUNAI, OF MOTOMACHI DORI, KOBE, JAPAN.

AUTOMATIC MATCH-MANUFACTURING MACHINE.

1,218,651.

Specification of Letters Patent. Patented Mar. 13, 1917.

Application filed January 11, 1917. Serial No. 141,787.

To all whom it may concern:

Be it known that I, SAKUSHIRO HATAKEYAMA, subject of Japan, residing at No. 119 Shichi-chome, Shimoyamate Dori, Kobe, Japan, have invented new and useful Improvements in Automatic Match-Manufacturing Machines, of which the following is a specification.

This invention relates to an automatic match manufacturing machine wherein a number of cylinders provided with a large number of rows of small holes bored at equal distances from one another are joined together at their both ends, with links of equal length, so that said cylinders and links form an endless chain which is made to move intermittently link by link. When the chain is stationary, some of the cylinders are made to rotate on their own axes by means of a pinion fixed to either side of each cylinder, for the purpose that the insertion, removal and tipping of splints may be executed at desired positions. The object of this invention is to replace the tape system with a cylinder system which not only saves much of the space generally occupied by machines of the tape system but by causing splints to rotate when they have been tipped, they are dried more easily and are tipped with more regular heads.

Figure 1 is a side elevation of the chief part of this invention; Fig. 2 is a plan of one of the cylinders when in the position for removing matches; and Fig. 3 is a section thereof on the line III—III. The same reference numbers refer to the same or corresponding parts throughout all the figures.

Around the cylinders small holes 2 are bored at equal distances from one another and in parallel lines, for inserting splints α .

On either side of a cylinder 1, on its axle 3, a helical pinion 4 is fixed, next the helical pinion 4 a roller 5 is mounted, then the axle passes through the edges of the two adjacent links 6, 6', and the whole is fastened down by a collar 7. In this way the links 6, 6' form an endless chain and connect the cylinders at equal distance. The aforesaid rollers 5 travel between the inner member 8 and the outer member 8' of a track provided on either side of the machine. On the inner side of the inner member 8 helical toothed racks 9 are fixed at certain intervals, so that when the cylinders are intermittently moved by one link by a suitable device, some of them may

be made to rotate on their own axes, thus the cylinder at the position A (Fig. 1) makes a rotation while it travels, and the splints it holds pass through a paraffin bath, while when at the position B (Fig. 1) the splints are exposed to drying draft more efficiently on account of the rotation. At the positions C, D and E (Fig. 1) the helical pinion 4 gears with worms 10 (Fig. 1) and the worms being moved a certain angular distance at a time, the cylinders are made to rotate just the breadth between two rows of the holes. Thus splints are planted in the holes at the position C by the automatic match manufacturing machine, Japanese Patent No. 29526, or any other suitable means; in the position D these splints are tipped from below and heads formed; and at the position E the cylinder stops at the upper end of the vertical part of the track and the heads of the splints on the cylinder are caught between the teeth of a comb 11 which is mounted parallel to the cylinder and moves backward and forward on the plane of the axis of the cylinder. The teeth of this comb 11 are curved downward and the spaces between them are broad enough at the foot to admit the heads b but toward the free ends they are narrowed and are just broad enough for splints but not for their heads. Thus receding motion of the comb pulls out the matches caught between its teeth. Then the rotation of the cylinder by the breadth between two rows brings the next row of matches into position for removal. In this way all the matches on the cylinder are pulled out and they are collected and arranged by any suitable device.

It is to be understood that this invention may be modified in details in many ways without departing from the spirit thereof.

Having thus described my invention, what I claim and desire to secure by Letters Patent is:—

1. An automatic match manufacturing machine characterized by a number of cylinders provided with rows of small holes bored at equal distances from one another all over the circumference and joined together by means of links in such a way that they form an endless chain, and by intermittent motion or traveling of said cylinders link by link and intermittent rotation of individual cylinders, substantially as and for the purposes hereinbefore set forth.

2. An automatic match manufacturing machine characterized by a number of cylinders provided with rows of small holes bored at equal distances from one another all around the circumference and joined together by means of links into an endless chain; by rotation on their own axes of individual cylinders caused by the gearing of worms with helical pinions fixed to both sides of cylinders which makes individual cylinders to rotate on their own axes; and by the gearing of said helical pinions with racks fixed to inner side of track which makes individual cylinders rotate on their own axes while traveling as a whole, substantially as and for the purposes hereinbefore set forth.
- 15 3. An automatic match manufacturing

machine consisting of cylinders having a large number of small holes all over the circumference and joined together by links, and provided with a device for removing matches consisting of a comb between the teeth of which they are admitted and caught at places where spaces between said teeth are narrowed and pulled out, substantially as and for the purposes hereinbefore set forth.

In testimony whereof I have signed my name to this specification in the presence of 30 two subscribing witnesses.

SAKUSHIRO HATAKEYAMA.
